MARKING MACHINE

Horace W. Hall, Newton, Mass.

Application October 28, 1931, Serial No. 571,579

12 Claims. (Cl. 33—189)

This invention relates to a marking machine, and more particularly to one devised to mark the places where holes for stringing are to be drilled in rackets for playing tennis, squash and other games.

One object of my invention is to provide a machine which will do all the hole marking for a racket simultaneously with absolute accuracy and by a simple operation. Other objects are to 10 make such a machine simple and inexpensive in construction, easy to operate and one that will stay practically always in good working order.

The foregoing and other objects which will appear as the nature of the invention is better understood, may be accomplished by a construction, combination and operative arrangement of parts such as is disclosed by the drawings. The nature of the invention is such as to render 15 it susceptible to various changes and modifications, and, therefore, I am not to be limited to the construction disclosed by the drawings; but am entitled to all such changes therefrom as fall within the scope of my claims.

In the drawings:

25 Figure 1 is a complete plan assembly of my marking machine with a racket in position to be marked.

Figure 2 is a partial cross-section taken on the line 2—2 of Figure 1, showing the cam and a 30 marking member in actuated position marking a racket.

Figure 3 is a cross-section on the line 3—3 of Figure 1, also showing the means which actuates the cam.

35 Figure 4 is a fragmentary portion of a racket showing some prick points made therein by my machine.

As illustrated a cam 12 gradually tapers outwardly and downwardly, and may be made of 40 wood or other material, being preferably covered at the sides thereof with a hardened steel band 13. The shape of the cam is determined by the shape of the racket to be punched or marked, being round for a squash racket and 45 oval for a tennis racket, et cetera.

The marking members are carefully positioned with relation to each other and the article to be marked so as to mark the racket at particular points that will insure even stringing, and they 50 are preferably made in two different lengths, the longer marking members 14 having a collar 15, and they abut against the cam 12 at their head end when in normal position. The shorter marking members 16 alternate with said longer members 14 and their heads are directly in front of

and contact with said collars 15 on each side thereof, as shown in Figure 1 of the drawings. There are coil springs 17 around said shorter marking members 16 which abut against a positioning form 18 later described. When the cam 60 12 is moved upwardly, being tapered and larger towards its lower end, it contacts with said longer marking members 14 pushing them forwardly, as illustrated in Figure 2 of the drawings, and, by reason of said collars 15, said shorter marking 65 members 16 are also pushed forwardly, forcing the prick points at the end of each of said marking members 14 and 16 into a racket far enough to make a slight depression in the wood. This actuation compresses said springs 17 against said 70 form 18 so that when pressure is released on said cam 12 said springs 17 force the return of the shorter marking members 16 to normal position, which in turn forces the longer marking members 14 back to normal too.

To expedite the marking operation I provide a positioning form 18 the shape of and slightly smaller than the inside of the racket to be marked, which surrounds said cam and has provision therein in the form of holes 19 into which the marking members 14 and 16 extend and rest, and which may be pushed far enough beyond to mark the racket. In Figures 1 and 3 of the drawings I have shown said marking members in slightly actuated position with the prick points 85 protruding a little beyond the outside of said positioning form 18 so they can be plainly seen. Normally these prick points are within said holes 19, except those that mark the holes at the throat or lower portion of a racket head which 90 in normal position, extend through said holes and beyond said form 18. This expedient is adopted because in tennis racket heads the length varies somewhat, and it is desirable to make the positioning form small enough to serve for any size 95 tennis racket, thus making it necessary only to use different length marking members for said throat portions in various size rackets.

In order to assure quick and correct positioning, and, therefore, marking of each racket or other article, said positioning form 18 has a guide mark 20 at the top, and at the bottom center thereof, and each racket 21 has a small groove or guide mark 22, so that when said top guide mark 20 100 and groove 22 are in alignment the prick points 105 will mark the places for the stringing holes in correct relation to each other. Said positioning form 18 is purposely made shorter in height than the racket 21 to be marked, so the operator can 110

readily see to line up the racket with said guide marks 20 and 22 opposite each other.

Said positioning form 18 is supported by a table 25 in which a recess 26 is cut to receive said form 18 and prevent any sidewise movement. Screws 27 hold said form 18 to said table 25 as shown in Figure 3 of the drawings. The cam 12 extends through an opening in said table 25, and the racket 21 to be marked rests on the top 10 thereof.

To actuate said cam upwardly any suitable and well known means may be employed. The mechanism I have shown consists of a flange 28 which is held by screws 29 to the under side of 15 said cam 12, into which flange the upper end of an upright member or vertical lever 30 screws, the lower end screwing into a lug 31. A forked, horizontal lever 32 is fastened to said lug 31 by a pin 33 which extends through said lug 31 and 20 forked end of said lever 32, said pin being held in place by a cotter pin 34. A standard 35 is forked at one end about said lever 32 by means of a pin 36 which serves as a pivot and which is held in place by a cotter pin 37. At the end of 25 said actuating lever 32 a foot treadle 38 is formed, downward pressure on which raises said lever 32 and the other movable parts to which said cam 12 is connected, forcing said cam upwardly and said marking members outwardly.

Fastened to said standard 35 is a stop member 30 40 which is recessed to receive a rubber bumper 41 on said lever 32, which parts 40 and 41 limit the downward movement of said cam 12, and determine the normal position thereof.

Said standard 35 is fastened to the floor 42, and 35 a coil spring 43 which is fastened around said pin 33 at one end is held to said floor 42 by an eye bolt 44 imbedded in said floor. Said spring 43 insures the immediate return of the cam to 40 normal position when pressure upon said foot treadle 38 is released.

What I claim is:

1. A marking machine comprising a cam, a plurality of marking members adapted to be actuated by said cam, spring means adapted to return said members, after being actuated, to normal position, a positioning form the shape of the article portion to be marked having provision to permit said members to project into and beyond it, said spring means abutting against said form, means to support said form, and means adapted to move said cam and thereby actuate said members.

2. A marking machine comprising a cam, 55 mechanism adapted to move said cam upwardly, a plurality of marking members adapted to be actuated by said cam, some of said members contacting directly with said cam and having means intermediate their ends against which other of 60 said members abut, spring means adapted to cause said members to return to normal position after being actuated, a positioning form having provision therein adapted to receive said members and to permit their projection beyond, and means to support said form.

3. A marking machine comprising a cam, means to actuate said cam, relatively long and short marking members distributed in alternating positions adjacent said cam, said long members being adapted to be directly actuated by said cam, a collar on each of said long members against which collars said shorter members abut, springs around 70 said shorter members, a positioning form against which said springs abut, said form having holes 75

into which said members extend and may project beyond, and a table to support said form.

4. A marking machine comprising a cam, means to actuate said cam, a table surrounding said cam, a positioning form surrounding said cam and resting on said table, said form having a plurality of holes therein, a plurality of marking members in contact with said cam and adapted to be actuated thereby, a plurality of other marking members spaced away from said cam, means on said first-mentioned marking members whereby their actuation also actuates said other marking members, said marking members extending into and adapted to project beyond said holes, and spring means in contact with said form adapted to return said marking members to normal position upon the return of said cam to normal position.

5. A marking machine comprising a vertical cam, mechanism to move said cam upwardly, a plurality of marking members adapted to be actuated by said cam, some of said members contacting directly with said cam and having means intermediate their ends against which other of said members abut, a positioning form for the article to be marked surrounding said cam and having provision to receive a portion of said members and permit their projection beyond said form, and means to support said form.

6. A marking machine comprising a cam, 105 mechanism adapted to move said cam upwardly, a plurality of marking members adapted to be actuated by said cam, some of said members contacting directly with said cam and having means intermediate their ends against which other of 110 said members abut, said other members having spring means contacting therewith adapted to return said members to normal position after being actuated, a positioning form for the article to be marked surrounding said cam having provision to receive a portion of said members and permit their projection beyond said form, and means to support said form.

7. A marking machine comprising a cam, means to move said cam, marking members adapted to be actuated by and one end of which contacts with said cam, collars on said marking members, other marking members contacting with said collars, springs around said other marking members adapted to be compressed when said cam 125 actuates said marking members, a positioning form for the article to be marked surrounding said cam against which said springs abut having holes extending therethrough into which all of said marking members extend, and means to support 130 said form.

8. A marking machine comprising a cam, means to move said cam, marking members adapted to be actuated by said cam, a collar on each of said marking members, other marking members in alternating positions to said first-mentioned marking members, said collar on each of said first-mentioned marking members contacting with two of said other marking members, means in contact with said other marking members adapted to return them to normal position after being actuated, a positioning form for the article to be marked surrounding said cam having holes extending therethrough into which all of said marking members extend, and means to 140 support said form.

9. A marking machine comprising a vertical cam which tapers outwardly and downwardly, means to move said cam upwardly, marking members one end of which contacts with said 150

cam, collars on said marking members, other marking members contacting with said collars, springs around said other marking members adapted to be compressed when said cam actuates said marking members, a positioning form adjacent said cam having provision therein to permit said marking members to extend into and beyond it, and means to support said form.

10. A marking machine comprising a vertical cam which tapers outwardly and downwardly, means to move said cam upwardly, a positioning form, a table supporting said form, relatively long and short marking members distributed in alternating positions, the heads of said long members contacting with said cam, collars on said long members, the heads of said shorter members being in contact with said collars, and coil springs around said shorter members abutting against said form, said form having holes therein into which said marking members extend and may project beyond.

11. A marking machine comprising a vertical cam which tapers outwardly and downwardly, a table having a recess therein, a positioning

form in said recess and surrounding said cam, means to move said cam upwardly, relatively long and short marking members in alternating positions, said long members contacting with said cam, collars on said long members, the heads of said shorter members contacting with said collars, coil springs around said shorter members abutting against said form, said form having holes therein opposite said marking members into which said members enter, said members being adapted to project beyond said holes upon actuation.

12. A marking machine comprising a vertical cam which tapers outwardly and downwardly, means to move said cam upwardly, a positioning form for the article to be marked, means to support said form, marking members adapted to be actuated by said cam, said positioning form having holes into which said members extend and may project beyond, and means in contact with said form to hold said marking members in position and cause their return to normal position after actuation.
